ABSTRACT

A toner bottle (38) has projections (38c, 38c') on its bottom surface. The projections (38c, 38c') extend in the axial direction but are spaced away from the central-axis line of the toner bottle (38). The projections (38c, 38c') are engaged with convex portions (62b, 62b') formed in a joint (62) of a drive portion (60). When the drive portion (60) starts rotating, the torque is transferred to the toner bottle (38) via the projections (38c, 38c') and the convex portions (62b, 62b'). Since the torque is transferred from the bottom side of the toner bottle (38), the toner bottle (38) can be attached to or detached from a body of an image forming apparatus in a direction of the central-axis line. Toner discharged from the toner bottle (38) is introduced into a process cartridge through an opening portion (48) of a toner hopper portion (40) and a toner introducing cover (52). A shutter member (88) is disposed in the toner introducing cover (52). The shutter member (88) consists of a flexible elastic member (90) and a holding member (92) for holding the elastic member (90). The shutter member (88) intersects with the opening plane of a toner supplying port. Guiding portions for bending and guiding the elastic member (90) along the toner supplying port are also disposed in the toner introducing cover (52).

**IMAGE FORMING APPARATUS, TONER
SUPPLY UNIT, AND TONER BOTTLE
ATTACHED THERETO**

BACKGROUND OF THE INVENTION

1. Field of the Invention

The present invention relates to an image forming apparatus, such as a copying machine, a printer, a facsimile machine and the like, a toner supply unit which supplies toner to a developing section of the image forming apparatus, and a toner bottle attached thereto.

2. Description of the Prior Art

A conventional image forming apparatus comprises a process cartridge including an image bearing medium, a developing unit, and the like, and a toner supply unit which supplies toner to a developing unit. Both the process cartridge and the toner supply unit are attachable to and detachable from the image forming apparatus. A toner supply port is formed on the side of the toner supply unit, whereas a toner receiving port is formed on the side of the process cartridge. The toner supply port faces the toner receiving port when the toner supply unit and the process cartridge are attached to the image forming apparatus.

In the image forming apparatus, toner can be supplied through the toner supply port and the toner receiving port facing each other. However, a construction is required in which the toner supply port is connected to the toner receiving port only when the toner supply unit is attached to the image forming apparatus from the viewpoint of avoiding damage to the apparatus or a poor work environment which is caused by scattered toner.

Therefore, prior art references ① to ① shown in the following have been proposed.

① An image forming apparatus in which a shutter member is disposed in a toner supply port and is driven to open and close the toner supply port by the fixing and releasing operation of a means for fixing and releasing a process cartridge which is operated after a process cartridge is attached to a body of the image forming apparatus body (Japanese Patent Application Early Laid-Open Publication No. Hei 2-201380).

② An image forming apparatus in which a shutter member is disposed in a toner supply port and is driven to open and close the toner supply port in accordance with the attaching and detaching operation of a toner cartridge with respect to a body of the image forming apparatus (Japanese Patent Application Early Laid-Open Publication No. Sho 56-120555). ③ An image forming apparatus in which a shutter member disposed in a toner supply port is driven by a clutch mechanism a driving source of which is a solenoid or the like (Japanese Patent Application Early Laid-Open Publication No. Hei 2-226268).

Generally, a toner bottle containing toner is mounted in a toner supply unit. It is well known that the toner bottle is attachable to and detachable from the toner supply unit. As regards the toner bottle which is freely attached to and detached from the toner supply unit, the following prior art references ④ to ⑤ have been proposed.

④ A toner supply unit in which a toner bottle is driven and rotated to an attaching and detaching position of the toner bottle a state in which the toner bottle has been connected to a developing unit, in other words, a state in which the toner bottle is held horizontally when the toner bottle is attached or detached (Japanese Patent Application Early Laid-Open Publication No. Hei 5-9194). Since this

rotating operation needs a space, it is carried out in the front of the image forming apparatus.

⑤ A toner supply unit in which a toner bottle is supported rotatably on fulcrum points formed in the outer both ends thereof and torque is transferred from at least one of the fulcrum points (Japanese Patent Application Early Laid-Open Publication No. Hei 3-2882).

Generally, in an image forming apparatus, an electrostatic latent image formed on a thin layer of photosensitive medium is visualized by adhesion of toner supplied from a developing unit, and a visible image is transferred onto a recording sheet. After that, it becomes a record object by a fixation process and is discharged out of the apparatus. Since toner is consumed by development, consumed quantity of toner is supplied with a toner supply unit. A so-called toner bottle containing toner is disposed in the toner supply unit attachably and detachably. The toner bottle is exchanged with a new toner bottle filled with toner, which is kept at hand, when the toner bottle becomes empty.

The toner bottle comprises a cylindrical body portion, a bottom portion by which one end thereof is closed, and a port portion for discharging toner which is formed into such a shape that the other end thereof is narrowed down. A spiral groove for transferring toner is formed extending from the body portion on the side of the bottom portion to the port portion in the inside wall ranging from the body portion to the port portion. Thereby, toner in the body portion passes through the spiral groove by rotation and is transferred to the outside, namely, the developing unit, via the port portion.

As mentioned above, the toner bottle is rotated by action of outside power, which is obtained from the side of the port portion in a conventional toner bottle. Prior art references ⑧ to ⑦ shown in the following have been proposed as this type of toner bottle.

⑥ A toner bottle in which a projection is formed at a portion having a difference in level or a so-called shoulder portion which is narrowed down in a port portion, and the projection is engaged with a claw portion for driving to rotate which is disposed in the toner supply unit and is connected to the source of a drive, and thereby the toner bottle can be rotated.

⑦ A toner bottle in which a secondary gear which is geared with a circumferential surface of the toner bottle is disposed near a port portion of the body portion, and a rotatable drive gear which is connected to a driving source is engaged with the secondary gear to rotate the toner bottle.

In the aforementioned prior art references, nonetheless, the image forming apparatus shown in reference ① does not have any shutter member for opening and closing a toner receiving port formed in a developing unit of an imaging unit, and thus, not only the corruption or destruction inside the apparatus may be caused by scattering toner, but also toner may scatter when the imaging unit is removed from the body of the image forming apparatus. Moreover, since it is composition of driving the shutter member by operating means for fixing the imaging unit after the imaging unit is mounted in the image forming apparatus, there can be trouble of complicating operation procedure.

While the image forming apparatus shown in reference ② is constructed to drive a shutter member by operation of attaching or removing a developing unit so that the improvement in operativity can be realized, the corruption or destruction inside the apparatus caused by scattering toner cannot be prevented from occurring because there is not any shutter member for opening and closing a toner receiving port of a developing unit, similarly to the aforementioned prior art reference ①.

In the image forming apparatus shown in reference ③, a clutch mechanism is used so that the cost of the entire apparatus falls into becoming higher.

Incidentally, it can be expected to be solvable in the problems described above if the shutter members are disposed in both the toner supply port and the toner receiving port and then are opened and closed by the operations of attaching to and removing from the image forming apparatus body which is a driving source.

In this case, it is general that each of the shutter members is moved parallel along the toner supply port and the toner receiving port, respectively.

In recent years when an image forming apparatus is miniaturized rapidly, however, there are many cases in which it is difficult in consideration of the configuration of an apparatus, arrangement and a layout space that each of the shutter members is moved parallel along the toner supply port and the toner receiving port, respectively.

In the image forming apparatus shown in reference ④, a vessel for containing toner is rotated in the front of the body of the image forming apparatus with respect to the attachment and removal of the toner containing vessel because the function of exchanging the toner containing vessel is required to heighten. As a result, a considerable space is required for the rotational operation so that the size of a whole apparatus needs to be enlarged regardless of the demand of miniaturizing the apparatus in recent years.

In the image forming apparatus shown in reference ⑤, a vessel for containing toner of which a toner discharging port is formed in the middle part of one end is used since this construction has an advantage of preventing toner from scattering. In the construction, however, a system of transferring a drive of rotational-driving means becomes complicated because the toner discharging port is formed in the Riddle part. Besides, a shaft member having a function of holding the central portion of the other end of the toner containing vessel needs to be used, which makes the cost of the apparatus higher.

In the toner bottle shown in reference ⑥, a toner transferring mechanism is disposed complicatedly in a part adjacent to the port portion and the claw portion for driving and members relevant thereto is disposed in this part. This construction may cause various problems such as complicating a structure, being incapable of miniaturizing an apparatus, and making it difficult to supply toner stably because the bottom side of the toner bottle is swayed easily.

In the toner bottle shown in reference ⑦, the toner bottle is rotated by the engagement with the drive gear adjacent to the JUDO gear, and then the force caused by the torque, by which the toner bottle slips toward the direction right-angled for the axis, is given to the toner bottle. Thus, normal rotation is not performed because of flotation or horizontal slips of the toner bottle in such a simple construction of the apparatus that the toner bottle is accommodated in a concave groove. In order to prevent those slips, the toner bottle is required to be supported by enclosing the entire circumference thereof, yet, if that is carried out, attachment-and-removal of the toner bottle cannot be operated smoothly.

SUMMARY OF THE INVENTION

It is therefore a first object of the present invention to provide an image forming apparatus which is capable of solving problems, such as toner scattering or high costs, and additionally capable of allowing the apparatus to be made small-sized in accordance with fixed conditions of, for example, a layout space.

It is a second object of the present invention to provide a toner supply unit which is capable of easily exchanging a toner receiving container in a relatively small space and which has low production costs and a compact-sized and simple construction.

It is a third object of the present invention to provide a toner bottle which has a simple construction and is easily attached and detached.

To achieve the objects, an image forming apparatus according to an aspect of the present invention comprises a toner supply unit which is directly or indirectly attached to and removed from a body of the image forming apparatus having a toner receiving port, a toner supply port which faces the toner receiving port when the toner supply unit is attached to the image forming apparatus body, and a shutter member for opening and closing the toner supply port. The shutter member has a bendable elastic member and a holding member for holding the elastic member and is disposed intersecting with an opening surface of the toner supply port. A guiding portion for bending and guiding the elastic member along the toner supply port is disposed in the toner supply unit.

In the image forming apparatus, an opening/closing function can be obtained certainly even in a case in which the shutter member which moves parallel along the toner supply port cannot be disposed for lack of an installed space. Thereby, the image forming apparatus can be constructed more freely, and additionally the apparatus can be made smaller-sized.

Preferably, in the image forming apparatus, there are formed a projecting portion in the shutter member, and a guiding rib which drives to open or close the shutter member by engagement with the projecting portion on the side of the image forming apparatus body.

The shutter member can be opened or closed by attaching and detaching the toner supply unit.

Preferably, in the image forming apparatus, there is formed an elastic sealing member with which an end of the elastic member is brought into contact when the toner supply port is closed by the shutter member in the toner supply unit.

In the image forming apparatus, a sealing function of preventing toner from scattering is improved without undergoing damage, such as breaking or bending, to the elastic member.

Preferably, in the image forming apparatus, there is formed a guide for regulating deformation by which the elastic member is regulated to deform while moving, facing the surface opposite to a surface on which the elastic member contacts the guiding portion in the toner supply unit.

In the image forming apparatus, bend and deformation of the elastic member required for opening and closing the toner supply port is certainly obtained without the elastic member being deformed unexpectedly even in a case in which the elasticity of the elastic member is insufficient.

Preferably, in the image forming apparatus, the toner receiving port and the guiding rib are disposed in a process cartridge in which at least an image bearing body and a developing unit are installed integrally to be able to be freely attached to and removed from the image forming apparatus body, and a second shutter member for opening and closing the toner receiving port is disposed in the process cartridge, and a second projecting portion is formed in the second shutter member. On the other hand, a second guiding rib for driving to open and close the second shutter member by

being engaged with the second projecting portion is disposed in the toner supply unit. The guiding rib and the second guiding rib each have a trapezoidal shape and intersect mutually in the direction of a convex.

In the image forming apparatus, opening-and-closing operation of both the shutter members can be performed regardless of the attachment-and-removal order of the toner supply unit and the process cartridge. Therefore, operational efficiency is improved. Moreover, a given space can be used effectively and the miniaturization of the apparatus can be achieved by the intersectional system of the guiding rib.

A toner supply unit according to an aspect of the present invention comprises a toner bottle having a toner discharging port in the middle part of an end of a cylindrical container body, a bottle holding means for holding the toner bottle substantially horizontally in a state in which toner can be introduced into a toner introducing portion of a developing unit from the toner discharging port, and a rotational driving means for rotating the toner bottle held on the bottle holding means around the central axis of the toner bottle in the longitudinal direction of the toner bottle, in which the toner bottle can be attached to and removed from the unit body in the direction of the central axis in a state in which the toner bottle is held by the bottle holding means.

In the toner supply unit, a toner receiving container can be attached to and removed from the unit body in a state of being held on the bottle holding means. Thereby, the space in the unit can be used effectively without spoiling the exchangeability of the toner receiving container, as well as, a miniaturization of the unit can be realized.

Preferably, in the toner supply unit, the toner bottle has a concave portion formed in the middle of the other end opposite to the end in which the toner discharging port is formed, and the rotational driving means has an engagement portion for transferring a driving force by engagement with the concave portion.

Preferably, in the toner supply unit, the engagement portion of the rotational driving means with the concave portion has both of the functions of positioning the toner bottle and transferring the rotational driving force and, in addition, the torque of the rotational drive can be made smaller.

Preferably, in the toner supply unit, the toner bottle has a convex portion formed in the middle of the other end opposite to an end in which the toner discharging port is formed, and the rotational driving means has an engagement portion for transferring a driving force by engagement with the convex portion.

A toner bottle according to an aspect of the present invention comprises a cylindrical body portion as a container for receiving toner, a bottom portion with which an end of the body portion is closed, and a port portion for discharging toner which is narrowly formed. The cylindrical body has a spiral groove for transferring toner which is formed in the inner wall of the body and extends from the body portion on the side of the bottom portion to the port portion. The toner is allowed to pass through the spiral groove by the rotation of the body and be discharged from the port portion. In the toner bottle, a projection in the axial direction for transferring a rotational force thereto is disposed at a position away from the central axial line of the cylindrical body portion outside the bottom portion.

In the toner bottle, since the driving force is obtained from the axial direction, a lateral slip perpendicular to the axis can be prevented and thereby toner is supplied stably. Furthermore, the construction of a driving system can be

made simple because the projection serving as the driving system and extending in the axial direction on the bottom side of the toner bottle on which there is a space enough to arrange other members.

5 Preferably, in the toner bottle, a center for determining a central position is disposed on the central axis outside the bottom portion. The center extends in the longitudinal direction more than the projection.

In the toner bottle, the connection of the driving system 10 with the projection can be automatically carried out on the basis of the center, thus being carried out smoothly and steadily.

Preferably, in the toner bottle, the bottom portion has a convex circumferential portion on which a ring with a predetermined width in the longitudinal direction is fitted rotatably by engagement means. The engagement means prevent the ring from coming off from a body of the toner bottle in the longitudinal direction when the ring rotates.

20 In the toner bottle, an inseparable connection between the ring and the toner bottle is ensured.

Preferably, in the toner bottle, the predetermined width of the ring is designed so that an end surface of the outer side of the ring in the longitudinal direction is located out of the 25 center.

In the toner bottle, since the surface of the ring is situated outside the projection which juts out of the bottom portion of the toner bottle, the toner bottle can be stood. Thus, the toner bottle is prevented from rolling or falling accidentally.

30 Preferably, in the toner bottle, a projection extending radially is formed in the circumferential surface of the ring. The projection is engaged with a concave portion of an immovable member.

In the toner bottle, since the ring rotatably holding the 35 toner bottle is fixed around the immovable member, the toner bottle can be rotated without generating vibration or slippage. Besides, the ring is easily attached to and detached from the immovable member.

40 Preferably, in the toner bottle, a projection for preventing the toner bottle from being interchanged with other types of toner bottles is formed in the ring.

In the toner bottle, an accident can be avoided which is caused by attaching a toner bottle other than a proper 45 predetermined toner bottle to the image forming apparatus by mistake.

Preferably, in the toner bottle, the engagement means 50 comprises a stopper formed in the inner part of the ring, an elastic claw, and the convex circumferential portion held between the stopper and the elastic claw.

In the toner bottle, an inseparable connection between the ring and the toner bottle is ensured.

Preferably, in the toner bottle, the diameter of the convex 55 circumferential portion is smaller than that of the body portion and is set so that the elastic claw is placed in an end plane space defined by a radial difference between the convex circumferential portion and the body portion in a state in which the ring is engaged with the toner bottle.

60 In the toner bottle, an inseparable connection between the ring and the toner bottle is ensured.

Preferably, in the toner bottle, a cylindrical intermediate portion is formed in a part closer to the bottom portion than the port portion inside the body portion. The cylindrical intermediate portion serves to hold the toner bottle and is engaged with a cylindrical bottle-holding member for leading toner discharged from the port portion by simultaneous

rotation with the toner bottle to a predetermined position. A small projection is formed in the peripheral part of the intermediate portion in order to position the toner bottle rotatably in a state in which the center of the toner bottle comes out in the inner circumferential part of the toner receiving stand.

In the toner bottle, since the toner bottle is rotated without rotational deflection, toner can be supplied stably.

Preferably, in the toner bottle, a cylindrical intermediate portion is formed between the port portion and the body portion. The cylindrical intermediate portion is engaged with a cylindrical bottle-holding member for holding the toner bottle and leading toner discharged from the front part of the bottle to a predetermined position by simultaneous rotation with the toner bottle. Further, driving claws are formed on the end surface of the intermediate portion on the side of the port in order to transfer torque to the bottle holding-member.

In the toner bottle, a member for conveying toner can be driven by the use of the rotation of the toner bottle.

BRIEF DESCRIPTION OF THE DRAWINGS

FIG. 1 is sectional view of an image forming apparatus.

FIG. 2 is perspective view of an internal construction of a process cartridge.

FIG. 3 is an exploded perspective view of a toner supply unit.

FIG. 4 is an exploded perspective view of a toner introduction cover.

FIG. 5 is a perspective view of a toner receiving stand and a guide plate the side of an apparatus body.

FIG. 6 is a perspective view of the toner supply unit to which a toner bottle is attached.

FIG. 24 is a bottom plan view of the toner bottle.

FIG. 25 is a perspective view of a ring and a bottom part of the toner bottle.

FIG. 26(a) is a sectional view of the ring cut by the P—P line of FIG. 26(b).

FIG. 26 (b) is a front view of the ring.

FIG. 27 is a sectional view of the ring fitted on the toner bottle.

FIG. 28 is a perspective view of the ring and the toner bottle, showing a state in which the toner bottle with the ring is erected.

FIGS. 29(a), 29(b) and 29(c) are views showing examples of various types of projections for preventing the toner bottle from being interchanged with other types of toner bottles.

FIG. 30 is a partially sectional view showing a state in which the toner bottle with the ring has been attached to the toner receiving stand and.

FIG. 31 is an exploded perspective view of the toner supply unit according to another embodiment.

FIG. 32 is a perspective view of the toner supply unit according to still another embodiment.

FIG. 33 is a perspective view of the toner supply unit according to still another embodiment, showing a state in which the toner supply unit has been drawn from the side of the apparatus body.

FIGS. 34(a) and 34(b) show a variant of a connection mechanism between a joint and the bottom part of the toner bottle, FIG. 34(a) shows an end surface of the joint, and FIG. 34(b) shows the bottom part of the toner bottle.

DETAILED DESCRIPTION OF THE PREFERRED EMBODIMENTS

Preferred embodiments of an image forming apparatus, a toner supply unit, and a toner bottle of the present invention will hereinafter be described in details in accordance with the accompanying drawings.

As shown in FIG. 1, an image forming apparatus 2 comprises a process cartridge 4 which is disposed in a state of being attachable to and removable from an image forming apparatus body (not shown), and a toner supply unit 6 which is disposed in a state of being attachable to and removable from the process cartridge 4. A photosensitive object 8 as an image bearing body and a developing unit 10 are placed integrally in the process cartridge 4.

A charged roller 12, a transfer roller 14, a cleaning blade 16 and the like are disposed around the photosensitive object 8. Agitating screws 18, 20, a development sleeve 22, a doctor blade 24 etc. are disposed in the developing unit 10. In FIG. 1, reference character 26 designates a toner recycling belt and reference character 28 designates a toner density sensor.

Imaging operation is performed as follows.

The surface electric potential of the photosensitive object 8 is reduced by an electric-charge-elimination light 32 and

is uniformized in the range of 0 to -150 V, and then it is charged until approximately -1100 V by the charged roller 12. Next, the surface electric potential of an area (image formed area) into which light has been projected in the photosensitive object 8 is exposed to light by exposure light 34 to a cone in the range of 0 to -290 V. Bias voltage of approximately -800 V is impressed on the development sleeve 22, and thereby the toner placed on the development sleeve 22 adheres to the image formed area.

The photosensitive object 8 in which the toner image has been formed rotates and then a transfer sheet is sent thereinto from a sheet supply portion, and then the transfer sheet is sent at a timing in which the forefront thereof corresponds to the forefront of the image at a position in which the transfer roller 14 comes in contact with the photosensitive object 8, and then the toner image on the surface of the photosensitive object 8 is transferred onto the transfer sheet at the position of the transfer roller 14 mentioned above. Thereafter, the transfer sheet is forwarded to a fixing portion (not shown), and then the toner is melted and adheres to the transfer sheet by heat and pressure and the transfer sheet is copied and sent out.

The remaining toner which remains on the photosensitive object 8 is scratched and removed by the cleaning blade 16, and thereafter, the remaining electric charge of the photosensitive object 8 is eliminated by the electric-charge-elimination light 32 so as to make the photosensitive object 8 in a purely white state in which the remaining toner is completely removed therefrom. Thereby, the imaging operation can be repeated.

The photosensitive object 8, the charged roller 12, the developing unit 10, the cleaning blade 16, etc. mentioned above are enclosed in a photosensitive-object enclosing case as a single formative member. The layout is shown in FIG. 2 as a perspective view. The remaining toner which has been scratched and removed from the photosensitive object 8 by the cleaning blade 16 is carried to the position of the toner recycling belt 26 by a toner carrying coil 30 which is disposed parallel to the photosensitive object 8, and then it is sent to a place for agitating a developing solution in which the agitating screws 18, 20 is disposed by the toner recycling belt 26. Accordingly, this mechanism allows toner to be recycled.

In the following, there is described the developing unit 10.

The development sleeve 22 has a fixed axis inside which a magnet of 5 poles is arranged, and also, the outside circumference side thereof is covered by pipe material of non-magnetism. The developing solution is moved on the development sleeve 22 by rotating the pipe material. Herein, the developing solution is a two-ingredient type which consists of a small iron ball (called a carrier) and toner. The developing solution circulates while being agitated by the agitating screws 18, 20, and thereby the toner is charged electrically and then carried to the surface of the photosensitive object 8 while adhering to the carrier. As a result, the toner becomes possible to adhere to the photosensitive object 8 in an action of electrostatic power. With respect to the developing solution, the carrier keeps circulating, but the toner is consumed by adhering to the image formed area on the photosensitive object 8. For this reason, toner needs to be supplied suitably. Moreover, inferiority or unevenness of the image depth may occur unless the developing solution is supplied in a certain quantity to the photosensitive object 8. Therefore, the doctor braid 24 for regulating the amount of inflow of the developing solution is disposed.

As shown in FIG. 1, the toner supply unit 6 comprises, upon the whole, a toner bottle 38, a toner receiving stand 42

for setting up the toner bottle 38 which is integrated with a toner hopper portion 40 on a side thereof, a bottle holding member 44 which is disposed in the toner hopper portion 40 to rotate integrally with the toner bottle 38, and further, a plurality of extruding members 46 which are disposed in the bottle holding member 44, wherein an opening portion 48 is formed in the toner hopper portion 40, and a member 50 for regulating the supply quantity is disposed on the outside surface of the opening portion 48 and has elasticity for correcting the supply quantity of toner, and further, a toner introducing cover 52 is disposed outside the opening portion 48 and a toner supplying port 54 is formed to open in the horizontal direction at the lower end of the toner introducing cover 52.

In the process cartridge 4, a toner receiving port 56 is formed to open in the horizontal direction above the agitating screw 20 of the developing unit 10, and then the toner supplying port 54 and the toner receiving port 56 face with each other when the process cartridge 4 and the toner supply unit 6 are mounted in the image forming apparatus body.

As shown by arrow A, the toner flows into the toner hopper portion 40 from a port portion 38a of the toner bottle 38 when the toner bottle 38 is rotated. Thereafter, the toner is pushed up in the direction of arrow B by the extruding members 46 of the bottle holding member 44 as the toner bottle 38 is rotated, and then flows in the direction of arrow C through the opening portion 48 to come into the toner introducing cover 52. Next, as shown by arrow D, the toner is supplied into the developing unit 10 through the toner supplying port 54 and the toner receiving port 56 which are connected with each other. Herein, the toner supplying port 54 and the toner receiving port 56 can be opened and closed by a shutter member mentioned later.

Next, there is described the toner supply unit 6 based on FIG. 3 to FIG. 8.

FIG. 3 shows parts of which the toner supply unit 6 consists. The toner bottle 38 is driven to rotate by a drive portion 60 which is fixed in a rear plate 58 (see FIGS. 5, 6 and 8) of the image forming apparatus body. The drive portion 60 consists of a joint 62, a spring 64, a case portion 66 having a motor and an axis inside thereof. A concave portion 62a and convex portions 62b, 62b' for being engaged with a cylinder are formed in the end part of the joint 62. In the lower part (the rear end) of the toner bottle 38a, as counterparts of those, there are formed a center 38b having a cylindrical convex portion for being engaged with the concave portion 62a of the joint 62, and projections 38c, 38c' in the axial direction having square-pillar convex portions for being engaged with the side surfaces of the convex portions 62b, 62b'. The bottom part of the toner bottle 38 is held by engaging the center 38b with the concave portion 62a, and further, the toner bottle 38 is rotated by engaging the axial-direction projections 38c, 38c' with the convex portions 62b, 62b'. As shown in FIG. 6, when the joint 62 of the drive portion 60 is rotated in the direction of arrow E, the toner bottle 38 is rotated in the same direction thereas.

A spiral groove 38D (see FIG. 22) is formed from the bottom to the port portion in the inside wall of the toner bottle 38, and is equivalent to the spiral groove 38d in the outside circumference thereof. The toner is discharged from the port portion 38a through the spiral groove 38D when the toner bottle 38 is rotated. A cap 68 for preventing the toner from being discharged while the toner is not in operation is disposed attachably and removably in the port portion 38a.

In the end side of the bottle holding member 44, a plurality of ribs 44a are formed integrally therewith, and the

11

extruding members 46 are stuck on the ribs 44a by a both-side tape, etc. Herein, the extruding members 46 consist of elastic material, such as MAIRA, rubber, or the like. A rib 44b is formed in the part opposite to the end part of the middle of the toner bottle 38 on the inside wall of the bottle holding member 44.

A middle portion 38-3 with the middle-sized diameter 13 formed between a cylindrical body portion with the largest diameter of the toner bottle 38 and the narrowed port portion 38a with the smallest diameter, and drive claws 38q, 38q' are formed in the end surface of the middle portion 38-3, a so-called shoulder portion, on the side of the port portion 38a. The drive claws 38q, 38q' are hooked by the rib 44b so that the bottle holding member 44 is rotated by rotation of the toner bottle 38.

In FIG. 3, reference character 70 designates a collecting chuck for holding and releasing the cap 68, and the collecting chuck 70 is placed inside a cylindrical case 72 and is connected with an axial member 76 by a screw 74. Reference character 78 designates seal material, 80 designates a seal member, and 82 designates a coil spring with which a series of parts such as the collecting chuck 70, the cylindrical case 72, the axial member 76 and such are in a state of being pressed toward the toner bottle 38. These mounted parts are held in a toner hopper portion 40. Reference character 84 designates a handle for opening or closing the port portion 38a by moving the cap 68, and an axial portion 84a formed integrally therewith is held rotatably on a hole 42a through which an axis is passed. Herein, the hole 42a is formed in the end part of the toner receiving stand 42.

Reference character 86 designates a slide axis formed in the axial member 76, which is inserted into a hole 76a. Herein, the slide axis 86 is in contact with a cam portion 84b which is formed in the handle 84. When the handle 84 is rotated in direction F shown in FIG. 5 and FIG. 6 and then the series of parts such as the collecting chuck 70 and the like are slid in the direction farther away from the toner bottle 38, the cap 68 is removed from the port portion 38a so that the toner in the toner bottle 38 can be discharged from the toner hopper portion 40. This mechanism will be described in details later.

Next, there will be described a shutter member and the like for opening or closing the toner supplying port 54 shown in FIG. 1.

As shown in FIG. 3, a member 50 for regulating the supply amount which is disposed in the opening portion 48 of the toner hopper portion 40 has a slit hole 50a (a hole which has been cut into a long and narrow square). Herein, the member 50 is made of elastic material such as MAIRA, rubber, or the like. The amount in which toner is supplied is made proper by the width of the slit hole 50a which is adjustable. The supply-amount regulating member 50 is stuck on the opening portion 48 by a both-side tape, etc.

Inside the toner introducing cover 52 which is disposed outside the opening portion 48, a shutter member 88 for opening or closing the toner supplying port 54 (see FIG. 4) is disposed movably in the upward and downward directions, that is, in a perpendicular state (an intersectional state) to the toner supplying port 54 which is opened horizontally. Herein, the shutter member 88 consists of an elastic member 90 as a shutter body which can be incurvated, a holding member 92 for holding the elastic member 90, and a cylindrical projection 94 which is formed integrally with a holding member 92. The holding member 92 has a spring member 96 whose stress allows the shutter member 88 to be kept closed. In this embodiment, the elastic

12

member 90, which is made of a polyester film such as MAIRA, etc. is stuck on the holding member 92 by a both-side tape, etc. A hole 52a within which the projection 94 is moved is formed in the toner introducing cover 52.

In the toner introducing cover 52, as shown in FIG. 4, the toner supplying port 54 is formed in the bottom surface thereof, and circular guiding portions 98, 98 for guiding the elastic member 90 of the shutter member 88 is formed integrally therewith. A sponge seal member 100 as an elastic seal member for preventing toner from scattering is disposed by fitting the end of the elastic member 90 into the end of the guiding portion 98.

Reference character 104, which is shown near the opening portion 48 in FIG. 3, designates a second guiding rib for driving a second shutter member mentioned later, which protrudes in the shape of a trapezoid in the longitudinal direction. Reference character 106 designates a guide for regulating deformation which holds the back side of the elastic member 90.

As shown in FIG. 5, the toner receiving stand 42 can be attached or detached freely in the directions of arrow G by being guided on a guide plate 108, and the guide plate 108 is fixed on a rear plate 58 and a front plate 59 of the apparatus body with screws (not shown). At the end of the guide plate 108, a stopper 112 for avoiding removal which is held a plate spring 110 fixed thereon is disposed. The toner supply unit 6 is attached in a state in which the stopper 112 has been pushed downward, and thereafter, the stopper 112 is returned to be engaged with the end part of the receiving stand 42. Thereby, the toner supply unit 6 is kept in a fixed state, as shown in FIG. 7.

In FIG. 5, there is shown a state in which the toner supply unit 6 is removed from the guide plate 108. In a state of being counted, side portions 42m, 42n are engaged with guides 108m, 108n of the guide plate 108. As shown in FIG. 5, in a state in which the receiving stand 42 has been drawn out, the toner bottle 38 is attached to or removed from the toner supply unit 6. As shown in FIG. 5, a step portion 42e formed in the receiving stand 42 is hooked by a notch portion 108a formed in the guide plate 108 so that removal can be prevented. A step portion 42d is hooked by a notch formed in the guide 108m. This notch is not shown in FIG. 5 since being hidden behind the apparatus-body front plate 59.

In FIG. 8, there is shown a state in which the process cartridge 4 has been counted and the toner supply unit 6 has been pulled out. In FIG. 8, the process cartridge 4 is positioned and held by a positioning pin (not shown) which is disposed in the rear plate 58 and the front plate 59 of the apparatus body and also is held not to be removed by a stopper 113 which is formed integrally with a upper case 41.

As shown in FIG. 5, the toner bottle 38 is placed on the receiving stand 42, and the toner supply unit 6 is pushed and set up into the apparatus body. Before that, there is kept a state in which the toner supplying port 54 which is formed in the bottom part of the toner introducing cover 52 has been closed with the shutter member 88 by the stress of the spring member 96, and the elastic member 90 is incurvated along the circular guiding portion 98 and the end thereof cuts into the sponge seal member 100. Thus, a seal is attached between the opening portion 48 of the toner hopper portion 40 and the toner supplying port 54 so that the toner can be prevented from leaking from therebetween.

When the operation of pushing the toner supply unit 6 into the apparatus body is carried out in the aforementioned state, the shutter member 88 goes upward (moves aside) into a

perpendicular state, and sequentially, the toner supplying port 54 is opened so that the developing unit 10 is linked to the toner supply unit 6. Next, the toner supply unit 6 is pulled out, and then the shutter member 88 goes downward and is incurvated along the toner supplying port 54 in the perpendicular state. Consequently, the toner supplying port 54 becomes a state of being closed.

Hereinafter, there will be described a shutter member and the like with which the toner supplying port 54 is opened or closed.

In FIG. 9, reference character 43 designates an upper case of a development portion, and a guide rib 114 which is engaged with the projection 94 and thereby allows the shutter member 88 to be rotated is formed integrally with the development-portion upper case 43. The guide rib 114, as shown in FIG. 10, is formed in the shape of a trapezoid having a projecting part in the perpendicular direction, and the guide rib 114 has inclination sides 114a, 114b, and a flat top side 114c. Herein, FIG. 10 is a side view seen from arrow H of FIG. 9.

Underneath the guide rib 114, as shown in FIG. 11, a second shutter member 115 for opening or closing the toner receiving port 56 is disposed substantially parallel to the toner receiving port 56. The second shutter member 115 consists of a plate-like shutter body 116 and a spring member 117 whose stress allows the shutter body 116 to be kept closed. A cylindrical second projecting portion 118, which is engaged with the second guiding ribs 102, 104 formed in the toner supply unit 6 and thereby allows the second shutter member 115 to be opened or closed in the longitudinal direction, is formed integrally with the shutter body 116. Slide pieces 116a are formed in the both sides of the shutter body 116, on the other hand, guide portions 41a with which slide pieces 116a are engaged is formed in the upper case 41. Thereby, the shutter body 116 slides longitudinally on the upper case 41. Further, in the under surface of the shutter body 116, a boss 116b which supports an end of the spring member 117 is formed integrally therewith, the other end of the spring member 117 is supported by a rib 41b in a square-U shape which is formed in the upper case 41.

In a state in which outside force does not act on the second projecting portion 118, in other words, a state in which the toner supply unit 6 is mounted in a predetermined position, the stress of the spring member 117 allows the shutter body 116 to be projected so that the toner receiving port 56 is closed. The position until which the shutter body 116 is projected is determined by the contact of the boss 116b with a step portion 41c. When the outside force acts on the second projecting portion 118, as shown in FIG. 12(b), the shutter body 116 is retreated against the stress of the spring member 117 so that the toner receiving port 56 is opened.

Next, on the basis of FIG. 13 and FIG. 14, there will be described the opening-and-closing operation of the shutter member 88 and the second shutter member 115, respectively.

Beginning with the state shown in FIG. 8, the toner bottle 38 is placed on the receiving stand 42, and then the toner supply unit 6 is pushed and set up into the apparatus body. Therefore, as shown in FIG. 13(a), there is kept a state in which the toner supplying port 54 has been closed with the shutter member 88 by the stress of the spring member 96, and the elastic member 90 is incurvated along the circular guiding portion 98 and the end thereof cuts into the sponge seal member 100. Thus, a seal is attached between the opening portion 48 of the toner hopper portion 40 and the toner supplying port 54 so that the toner can be prevented

from leaking from therebetween. In FIG. 13(a), reference character 52d designates a concave portion for receiving a spring which is formed on the toner introducing cover 52, and 92a designates a spring seat which is formed integrated with the holding member 92.

When the operation of pushing the toner supply unit 6 into the apparatus body is carried out in the aforementioned state, the cylindrical part of the projection 94 which is formed integrally with the holding member 92 comes into contact with a inclining side 114a of the guide rib 114 which is formed integrally with the development-portion upper case 43. As shown in FIG. 13(b), the cylindrical part is pushed upward against the stress of the spring member until reaching and stopping at a flat top part 114c of the guide rib 114. Following this movement, the elastic member 90 goes upward (moves aside) along the guiding portion 98 so that the toner supplying port 54 is opened.

The projection 94 is slid downward on the inclining side 114a when the toner supply unit 6 is drawn out, and then the shutter member 88 is moved toward the direction of being closed automatically by the stress of the spring member 96. Sequentially, the elastic member 90 is incurvated along the toner supplying port 54 from a perpendicular state and then is brought to a closed state shown in FIG. 13(b). In this embodiment, the deformation-regulation guide 106 is disposed on the back side of the elastic member 90 so that the unexpected deformation (waving, etc.) under movement of the elastic member 90 can be prevented, as well as, no more than incurvate deformation which allows the toner supplying port 54 to be opened or closed can be made without fail. Herein, yet, the deformation-regulation guide 106 is not necessarily used.

In this embodiment, there has been described the operation in which the shutter member 88 is opened or closed in the case where the toner supply unit 6 is attached to or removed from the process cartridge 4 which has been mounted in the apparatus body. Herein, the guide rib 114 is formed in the shape of a trapezoid, and thus, opening-or-closing operation of the shutter member 88, which is similar to the aforementioned operation, can be made in each cases where the toner supply unit 6 or the process cartridge 4 is attached to or removed from the apparatus body, regardless of the order by which each of the attachment-or-removal operations is carried out. Thereby, in each cases where the toner supply unit 6 or the process cartridge 4 is removed from the apparatus body, the shutter member 88 is closed. Thus, the toner can be prevented from scattering.

On the other hand, when the toner supply unit 6 is pushed in, as shown in FIG. 14(a), the cylindrical second projecting portion 118 comes in contact with a inclining side 102a of a second guide rib 102 which is formed to protrude in the longitudinal direction in the receiving stand 42 of the toner supply unit 6. As shown in FIG. 14(b), the second shutter member 115 is moved aside from the closed state thereof in the longitudinal direction against the stress of the spring member 117. Thereafter, the toner receiving port 56 is opened fully at the time that the second projecting portion 118 passes through the inclining side 102a, and then the toner receiving port 56 and the toner supplying port 54 face to each other when the second projecting portion 118 reaches at the central part of the side of the toner introducing cover 52 (see FIG. 14(c)). Since both of the operations in which the second shutter member 115 is opened, and the shutter member 88 is opened, occur simultaneously, the developing unit 10 and the toner supply unit 6 are connected to each other.

The second guide ribs 102, 104 have a separation form in which the toner introducing cover 52 is disposed in the

15

middle part thereof. Nonetheless, the second guide rib **102** practically has a function similar to the guide rib **114** since having an inclining side **104a** with which the inclining side **102a** is symmetrized. As a consequence, the order by which the process cartridge **4** and the toner supply unit **6** is attached to or removed from the apparatus body therebetween even in the operation where the second shutter member **115** is opened or closed.

In the second guide ribs **102, 104** which is disposed in the toner supply unit **6**, reference character **L** designates a distance between the central point of the toner supplying port **54** and the end point of the inclining side (see FIG. 14(a)). On the other hand, in the guide rib **114** which is disposed in the development-portion upper case **43** of the process cartridge **4**, reference character **l** designates a length of the inclining side **114a** in the attachment-or-removal direction (see FIG. 10). Herein, the relation between **L** and **l** are determined to become $L > l$, and thereby the shutter member **88** is opened or closed on the side of the toner supplying port **54** in a state in which the second shutter member **115** on the side of the toner receiving port **56** is kept opened.

Next, there will be described a mechanism in which toner is supplied from the toner supply unit **6** to the process cartridge **4**. FIG. 15 shows a state in which both of the toner supplying port **54** and the toner receiving port **56** is opened, that is, the toner supply unit **6** and the process cartridge **4** is attached to the apparatus body. As shown in FIG. 15, a small globular projection **38f** is formed in the middle portion **38-3** (see FIG. 3) of the toner bottle **38**. The small projection **38f** is engaged with the inner circumference of the bottle holding member **44**, and then the end surface of the toner bottle **38** is engaged with the rib **44b** of the bottle holding member **44**. Thereby, the toner bottle **38** is positioned over the toner hopper portion **40**.

In this state, the slide axis **86** is pulled in the direction of arrow **J** shown in FIG. 15 by the cam portion **84b** (see FIG. 3) when the handle **84** is rotated downward in the direction of arrow **F** shown in FIG. 5 and FIG. 6. Thereby, the axial member **76** is moved in the direction of arrow **J**, and then the collecting chuck **70** comes into contact with a projection **72a** of the cylindrical case **72** and begins to be closed so as to collect the cap **68**. When more movement in the direction of arrow **J** is made, as shown in FIG. 15, the cap **68** of the toner bottle **38** is removed by the collecting chuck **70** so that toner **Tn** in the toner bottle **38** can be flown into the toner hopper portion **40** which is mounted on the toner receiving stand **42**.

Toner supply is made on the basis of the toner density inside the developing unit **10** which is detected by the toner density sensor **28** (FIG. 1). First, the drive portion **60** begins to operate and rotates the joint **62** in the direction of arrow **E** when a detected value becomes below a predetermined density, as shown in FIG. 6. Thereby, the joint **52** becomes engaged with the bottom part of the toner bottle **38**, and then the toner bottle **38** is also rotated in the direction of arrow **E**. The toner is discharged from the port portion **38a** and is accumulated in the toner hopper portion **40** when the toner bottle **38** is rotated. On the other hand, the drive claws **38q, 38q'** which are formed on the end side of the port portion side of the middle portion **38-3** of the toner bottle **38** becomes engaged with and pushes to move the rib **44b** which is formed integrally with the bottle holding member **44** by the rotation of the toner bottle **38**. Therefore, the extruding member **46** which is formed integrally with the bottle holding member **44** is rotated rubbing on the inner wall of the toner hopper portion **40**. The toner **Tn** which remains inside the toner hopper portion **40** is scratched up by the rotation of the extruding member **46**.

16

When the extruding member **46** passes through a slit hole of the supply-quantity regulating member **50**, the toner is pushed out of the slit hole, and then the toner falls inside the toner **a** introducing cover **52** and passes through the toner supplying port **54** and the toner receiving port **56** which are located in the lower part in a open state, and finally, the toner is supplied into the developing unit **10**.

Next, on the basis of FIG. 17 to FIG. 30, there will be described in details the toner bottle according to this invention.

In FIG. 17 to FIG. 24, there is described a basic construction of the toner bottle according to this invention, and in FIG. 17 to FIG. 24, there is described the toner bottle which has a member such as a ring in order to raise use value thereof, in addition to the basic construction of the toner bottle.

FIG. 17 is a perspective view of the toner bottle, showing the basic construction thereof. In FIG. 17, view arrows **a** to **e** designate view directions for grasping the toner bottle. FIG. 18 is a front view of the toner bottle, showing a configuration thereof of being viewed from the direction of view arrow **a**. Likewise, FIG. 19 is a back view of the toner bottle, showing a configuration thereof of being viewed from the direction of view arrow **b**. FIG. 20 is a right-side view of the toner bottle, showing a configuration thereof of being viewed from the direction of view arrow **c**. FIG. 21 is a left-side view of the toner bottle, showing a configuration thereof of being viewed from the direction of view arrow **d**. FIG. 23 is a top plan view of the toner bottle, showing a configuration thereof of being viewed from the direction of view arrow **e**. FIG. 24 is a bottom plan view of the toner bottle, showing a configuration thereof of being viewed from the direction of view arrow **f**. FIG. 22 is a sectional view of the toner bottle which has been cut by the **K-K** line in FIG. 18.

EXAMPLE A

In FIG. 17 to FIG. 30, reference character **38-1** designates a cylindrical body portion, and an end thereof is closed. This closed part is shown as a bottom portion **38-2**. The port portion **38a** from which the toner is discharged is formed in the narrowed part of the other end of the body portion **38-1**. In the inner wall from the body portion **38-1** to the port portion **38a**, the spiral groove **38D** through which the toner is transferred is formed continuously from the body portion **38-1** on the side of the bottom portion **38-2** toward the port portion **38a**. Herein, the spiral groove **38D** is equivalent to the spiral groove **38d** in the outside circumference thereof. Incidentally, for convenience sake, the toner bottle **38** is shown in a state in which the opening of the port portion **38a** is directed upward in FIG. 17 to FIG. 22, however, as shown in FIG. 15 and FIG. 16, the toner bottle **38** is mounted in the toner supply unit **6** practically in a state in which the port portion **38a** is directed longitudinally. If the toner bottle **38** is rotated, the toner in the toner bottle **38** is guided by the spiral groove **38D** and then is sent outside through the spiral groove **38D**.

In a position outside the bottom portion **38-2** and away from a cylindrical central-axis line **0—0**, as shown in FIG. 18 and FIG. 24, there are formed projections **38c, 38c'** in the axial direction which has a square-pillar-like convex portion. Herein, The projections **38c, 38c'** is used for transferring torque to the toner bottle **38**. In this example, a square-pillar-like convex portion is used as the axial-direction projections **38c, 38c'**, yet, configuration thereof is not restricted to this, in other words, any configuration

whose portion is engaged easily with the convex portions **62b**, **62b'** which are driving sources of the torque can be used whereas. As shown in FIG. 30, in a nutshell, any projection can be suitable if it is engaged with the convex portions **62b**, **62b'** of the joint **62** which is rotated pivoting on an axial line **0**. Accordingly, the joint **62** is rotated in the direction of arrow **E**, and thereby the convex portion **62b**, **62b'** are engaged with the axial-direction projections **38c**, **38c'**, respectively so that the toner bottle **38** is rotated. In this case, needless to say, the port portion **38a** is held rotatably by holding means.

As mentioned above, the axial-direction projections **38c**, **38c'** for transferring torque is formed not on the side of a port portion through which toner is discharged but on the side of the bottom portion **38-2**, and thereby vibration on the side of the port portion **38a** can be lessened. In addition, the two axial-direction projections **38c**, **38c'** whose center is on the central-axis line **0—0** and which are spaced away from the central-axis line **0—0** is formed, and thus, substantially a couple of torque work. Thereby, any force which is thrown off in the radius direction is not given to the toner bottle **38** even while the toner bottle **38** is rotated. As a result, the necessity of making the countermeasure for preventing the toner bottle **38** from being thrown off is eliminated or lightened so that the construction can be simplified as well as stable supply of toner can be realized.

EXAMPLE B

Outside the bottom portion **38-2** and on the central-axis line **0—0**, a cylindrical center **38b** for determining the central position thereof is formed to project by Δh in the axial longitudinal outward direction from the axial-direction projections **38c**, **38c'** (see FIG. 18). The cylindrical center **38b**, as shown in FIG. 3 and FIG. 5, is inserted into the concave portion **62a** of the joint **62**, and thus, the bottom part of the toner bottle **38** is held at a position. Especially, the reason why the cylindrical center **38b** is projected by Δh in the axial longitudinal outward direction from the axial-direction projections **38c**, **38c'** is as follows.

In brief, the position in which the joint **62** stops rotating is unstable, and thus, there is a possibility that the position of the convex portion **62b**, **62b'** say be overlapped with the axial-direction projections **38c**, **38c'** when the toner bottle **38** is mounted. In this case, the torque cannot be transferred by engaging the convex portion **62b**, **62b'** with the axial-direction projections **38c**, **38c'**. As shown in this embodiment, however, if the center **38b** is made higher than the axial-direction projections **38c**, **38c'** at least the end part of the center **38b** is inserted into the concave portion **62a**. Therefore, the joint **62** can be rotated even in a state in which the position of the convex portion **62b**, **62b'** is overlapped with the axial-direction projections **38c**, **38c'**. As a consequence, the position of the convex portion **62b**, **62b'** is deviated from the axial-direction projections **38c**, **38c'**.

On the other hand, the stress of the spring **64** keeps placed on the joint **62**, and thus, the joint **62** falls automatically into the axial-direction projections **38c**, **38c'** and thereby the rotation of the joint **62**, as shown in FIG. 30, leads to a state in which the torque can be transferred to the toner bottle **38** when the position of the convex portion **62b**, **62b'** is deviated from the axial-direction projections **38c**, **38c'**.

Accordingly, there is not required the control of stopping the joint **62** at a specific rotational position in this embodiment.

EXAMPLE C

The cylindrical middle portion **38-3** which holds the toner bottle **38** and also is engaged with the bottle holding member

44 is formed the port portion **38a** in a part closer to the bottom portion **38-2** than the port portion **38a**. The bottle holding member **44** is formed cylindrically and leads the toner discharged from the port portion **38a** to a predetermined part by rotating synchronously with the toner bottle **38**. The middle portion **38-3**, which is a part of the body portion **38-1**, is smaller in diameter than the body portion except therefor and larger than the port portion **38a**. Naturally, the spiral groove **38D** is also formed in the inner wall of the middle portion **38-3**.

In the outer circumferential part of the middle portion **38-3**, as shown in FIG. 15, the small projection **38f** which is brought into contact with the inner circumferential surface of the bottle holding member **44** and holds the toner bottle **38** without its being deviated from the rotational center of the bottle holding member **44** is formed. The small projection **38f** is formed at positions where the circumference thereof is divided at regular intervals so as to come into contact uniformly with the inner circumferential surface of the bottle holding member **44**. In this example, four small projections **38f** are formed at intervals of an angle of 90° . Although the number of the small projections **38f** may be more or less than four pieces in addition to four pieces in this example, the minimum values are limited to 3 pieces or a 120 degrees interval in order to stabilize the position. Herein, the size of the small projections **38f** is determined by the relation in inner diameter between the middle portion **38-3** and the bottle holding member **44**. In consideration of the easiness of attaching or removing the toner bottle **38**, it is desirable that the small projections **38f** is brought into contact with the bottle holding member **44** by the extent to which the contact pressure thereof does not become excessively high.

In the case mentioned above, the stall projections **38f** is held accurately on the inner radius part of the bottle holding member **44**, and thereby the toner bottle **38** and the body portion **38-1** are located rotatably by being centered on the incircumferential inner radius part for holding a toner bottle which is formed in the toner receiving stand **42**. Hence, the toner bottle **38** is rotated without being vibrated so that stable supply of toner can be realized.

EXAMPLE D

The drive claws **38q**, **38q'** are formed projecting in the direction of the central-axis line **0—0** in the end surface of the middle portion **38-3**, the so-called shoulder portion, on the side of the port portion **38a**. The drive claws **38q**, **38q'** are hooked by the bottle holding member **44**, in more detail, the rib **44b** which is rotated synchronously with the bottle holding member **44** so that the extruding member **46** is rotated. Herein, the drive claws **38q**, **38q'** are disposed facing to each other in the diametrical direction of the middle portion **38-3**. The rotation of the toner bottle **38** is transferred to the bottle holding member **44** through the medium of the rib **44b** by the drive claws **38q**, **38q'**.

Since the drive claws **38q**, **38q'** and the rib **44b** are formed by small pieces, there is only a little probability by which they collide with each other in the axial direction in the case where the toner bottle **38** moves in the axial direction. The extruding member **46** is rotated by the rotation of the bottle holding member **44**, and thereby the toner which has been discharged from the port portion **38a** and transferred into the toner hopper portion **40** is scratched up. Thereafter, the toner is flown from the opening portion **48** into the developing unit **10** through the toner supplying port **54**.

According to this construction in which the simple drive claws **38q**, **38q'** protrude from the end side of the middle

19

portion 38-3, the toner in the toner hopper portion 40 can be carried automatically outside the toner hopper portion by being rotated with the toner bottle 38 without any other driving means.

EXAMPLE E

A ring 120 shown in FIGS. 25, 26(a) and 26(b) can be fit rotatably in the bottom portion 38-2 of the toner bottle 38 which is shown in FIG. 17 to FIG. 24 so that it say not shift in the axial-longitudinal direction of the toner bottle 38 during rotation. FIG. 26(a) is a sectional view of view arrow P—P shown in FIG. 26(b). An convex outer circumferential portion 38-2a which is formed in the bottom portion 38-2, three elastic claw members 120-1a, 120-1b, 120-1c which are formed in the inner circumferential part of the ring 120, three stoppers 120-1A, 120-1B, 120-1C which are formed in the inner circumferential part of the ring 120, and the like, as shown in FIGS. 25, 26(a) and 26(b), are used as engagement means for engaging the toner bottle 38 with the ring 120 by which deviation thereof can be avoided. Besides, A groove designated by reference character 38-4 in FIG. 18, etc. is formed between the convex outer circumferential portion 38-2a and the body portion 38-1.

The three elastic claw members 120-1a, 120-1b, 120-1c are disposed at three positions, by which the inner circumference of the ring 120 is divided at an equal interval, on the inner circumference thereof. The three elastic claw members 120-1a, 120-1b, 120-1c consist of holding-by-one-side elastic members, one of whose ends is integrated with a ring body. Holding-by-one-side stopper holding members are disposed between each of the three elastic claw members 120-1a, 120-1b, 120-1c, and the stoppers 120-1A, 120-1B, 120-1C are formed in the three stopper holding members.

The parts on the basic end sides of the three elastic claw members 120-1a, 120-1b, 120-1c and the three stopper holding members are divided by the tedium of SURIWARI portions, yet, a have a construction of a circular inner circumferential surface as a whole, and in addition, they are of a size by which rotation can be made rubbing without generating any rotational vibration when being engaged with the convex outer circumferential portion 38-2a.

The three elastic claw members 120-1a, 120-1b, 120-1c have a fluke-like shape, that is, a shape of being bent in the inward direction, in the free ends thereof. As shown by arrow Q in FIG. 25, the ring 120 is fit in the toner bottle 38 by being pushed into the convex outer circumferential portion 38-2a, and thereat, the free ends of the three elastic claw members 120-1a, 120-1b, 120-1c yield, and then the claw parts thereof go beyond the convex outer circumferential portion 38-2a to cone into the groove 38-4. On this occasion, the convex outer circumferential portion 38-2a is seized by the three elastic claw members 120-1a, 120-1b, 120-1c and the stoppers 120-1A, 120-1B, 120-1C, in a state in which flexible rubbing movement thereof is maintained. Hence, the ring 120 is designed to avoid being detached easily once having been engaged, which allows the ring 120 to function sufficiently. Each of the three elastic claw members 120-1a, 120-1b, 120-1c has a rectangular bent-up portion to be fit in the rectangular part around the convex outer circumferential portion 38-2a in order to avoid being detached, and thus, the rectangular part is fit in the rectangular part around the convex outer circumferential portion 38-2a so that coming-off in the axial direction and separation can be prevented.

In short, the convex outer circumferential portion 38-2a is grasped by the three elastic claw members 120-1a, 120-1b,

20

120-1c and the stoppers 120-1A, 120-1B, 120-1C so that the toner bottle 38 can be rotated over the ring 120 without being deviated.

EXAMPLE F

As shown in FIG. 27, an end of the ring 120 is opposite adjacently to the periphery of an end of the body portion 38-1 of the toner bottle 38, and further, the convex outer circumferential portion 38-2a is smaller in diameter than the body portion 38-1, and the end surface part of the toner bottle 38 which is defined by the difference in diameter covers the elastic claw members 120-1a, 120-1b, 120-1c. As mentioned above, moreover, the toner bottle 38 cannot move over the ring 120 in the axial direction, and thus, the three elastic claw members 120-1a, 120-1b, 120-1c cannot be operated from outside, which virtually makes it impossible to remove the ring 120. If the ring 120 has been forcibly detached by external force, the convex outer circumferential portion 38-2a of the toner bottle 38 may be broken.

The ring 120 is fixedly engaged with the toner bottle 38 because the ring 120 needs to be integrated securely with the toner bottle 38 so that the ring 120 can have one or more functions among a function of irreplaceability, a function as a stand and a function of preventing rotation, as shown in the following.

EXAMPLE G

An example, which will be mentioned in the following, is concerned in a stand function of the ring 120. The ring 120 has a predetermined width W in the axial longitudinal direction. FIG. 27 is a sectional view, showing a case where the ring 120 is cut by the line corresponding to the sectional plane of view arrow P-O-B' in FIG. 26(b) in a state in which the ring 120 is fit in the convex outer circumferential portion 38-2a of the toner bottle 38. As seen in FIG. 27, the predetermined width W is determined to make an end of the ring 120 brought in contact with the end surface of the body portion 38-1 of the toner bottle 38 in a mounted state, as well as to make the other end thereof located in a more outward direction than the center 38b. In a nutshell, the other end of the ring 120 is made higher by Δt than the outer plane of the center 38b. Consequently, not only the center 38b but also the axial-direction projections 38c, 38c' lie in a more inward direction than the other end of the ring 120.

Accordingly, the toner bottle 38 in which the ring 120 has been mounted, as shown in FIG. 28, can be stood on a plane of a table 130 or the like. Without this type of ring 120, the center 38b protrudes from the bottom of the toner bottle 38 so that the toner bottle 38 cannot be stood, as shown in FIG. 12. Therefore, a cylindrical toner bottle is held on its side in a state of being easy to roll in such a case that the toner bottle is exchanged, and thus, the toner bottle may drop from a table or the like to a floor. In this respect, if the ring 120 is used, as shown in this example, a toner bottle is stood in a stable state so that the fall accident thereof can be decreased.

EXAMPLE H

This embodiment is concerned in a function of preventing the ring 120 from rotating.

In the peripheral part of the ring 120, as shown in FIG. 25, there is formed a projection 120-4 in the radius direction which has a predetermined configuration and size so as to become engaged with a concave portion 200 which is formed in the toner receiving stand 42 as an immovable member. In this example, the radius-direction projection

120-4 is shaped like a rectangular parallelepiped. On the other hand, the concave portion **200** which is formed in the toner receiving stand **42** has a size and a rectangular configuration by which the concave portion **200** can be engaged with the radius-direction projection **120-4**. As shown in FIG. 5, the toner bottle **38** is mounted in the toner receiving stand **42** by inserting the radius-direction projection **120-4** into the concave portion **200**.

If the attachment is done by the method mentioned above, the ring **120** can be prevented from rotating over the toner receiving stand **42**, as well as, the toner bottle **38** is held and rotated stably on the ring **12** as a bearing since the ring **120** is positioned precisely on the basis on the relationship between the radius-direction projection **120-4** and the concave portion **200**. Furthermore, the radius-direction projection **120-4** can be engaged with the concave portion **200** merely by raising the ring together with the toner bottle as having a simple structure of being protruded outwardly. Accordingly, the attachment-or-detachment operation is carried out without difficulty.

EXAMPLE I

This example is concerned in a function of irreplaceability of the ring **120**.

The ring **120** has a projection **120-5** for preventing a predetermined type of toner bottle from being exchanged by the other types of toner bottle in the part opposite to the radius-direction projection **120-4** in the radius direction. The projection **120-5** is shaped to have a specific relation corresponding to the toner bottle **38**. In this example, the projection **120-5** has a plate-like shape.

On the front plane of the apparatus-body front plate **69**, as shown in FIG. 5, there is disposed a discerning member **141** having a MIZO 140 which has a width of being coupled with a certain ring, for instance, the projection **120-5** of the ring **120**. The discerning member **141** is positioned to be joined together with the toner bottle **38** containing toner used for the image forming apparatus and the ring **120** attached to the toner bottle **38**.

If a toner bottle to which the ring **120a** hating the projection **120-5** is attached is used, as shown in FIG. 5, the position of the projection **120-5** corresponds to that of MIZO 140 so that the toner bottle **38** can be set up without any problem. With respect to a user side or maintenance service side, as shown in FIGS. 29(a), 29(b) and 29(c), various types of projections **120-5a**, **120-5b**, **120-5c**, etc., each of which is different from each other in its position or shape, may be used for a variety of image forming apparatuses.

Even though a toner bottle having a ring which has any one of the projections **120-5a**, **120-5b**, **120-5c**, etc., attempts to be installed by mistake in the toner supply unit **6** shown in FIG. 5, the toner receiving stand **42** is prevented from being moved in the more inward direction than a point of place where the discerning member **141** is disposed and then from being set up in the toner supply unit **6** because all of the projections **120-5a**, **120-5b**, **120-5c**, etc., differ in disposed position or configuration from the projection **120-5**. In brief, the ring **120** has an irreplaceability function of the toner bottle **38** so that a toner bottle different from the toner bottle containing toner peculiar to the image forming apparatus can avoid being selected.

In many cases where different kinds of toner is used in terms of the combination of mixing additives as charge control materials, depending upon the developing speed of various types of image forming apparatuses, the image forming function may be damaged if toner which is not

matched to the property is used. Accordingly, an irreplaceability function as mentioned in this example is significant.

Incidentally, in this embodiment, the projection **120-5**, which protrudes outwardly in the radius direction of the ring **120** is shown as an example, yet, the projection **120-5** may protrude inwardly. In short, the position or configuration of a projection say be determined at will so far as the discerning member **141** has a function of choosing a single type of projection among others.

All of the three constructions relating to the aforementioned functions, that is, the function of irreplaceability, the function as a stand and the function of preventing rotation, may be used in a single ring, and naturally, a ring may be constructed to use only one function among them.

Besides, ribs **120a**, **120b**, **120c** are formed in the ring **120**. The ribs **120a**, **120b**, and the rib **120c**, come into contact with the guide **108n**, and the guide **108m**, respectively. Thereby, the guiding operation can be stabilized and also the positioning accuracy can be heightened at the time that the ring **120** is inserted into the toner receiving stand **42**.

In the ring **120**, the side of the radius-direction projection **120-4** is shaped substantially circularly, compared with the side of the projection **120-5**. On the other hand, the side of the projection **120-5** projects angularly on the both end sides thereof. This configurational characteristic enables an operator not to mistake the side of the projection **120-5** for the side of the radius-direction projection **120-4**, and vice versa. In other words, it can be easily judged that a projection on the side of being shaped substantially circularly is equivalent to the radius-direction projection **120-4**, and a projection on the other side is equivalent to the projection **120-5** by making the configuration of the ring **120** asymmetric. As a consequence, misjudgment can be avoided.

Next, other embodiments according to this invention is shown in FIGS. 31 to 34.

In the rear-end of the toner bottle **38** according to this embodiment, as shown in FIG. 31, there is not inserted a ring (reference character **120** in FIG. 30). No sore than the supply-amount regulating member **50** having the slit hole **50a** is disposed in the opening portion **48** of the toner hopper portion **40**, in a nutshell, a shutter member (reference character **88** in FIG. 30) is not disposed therein. In addition, a handle **84'** having a configuration different from the handle **84** is used.

The amount of toner supply can be regulated properly by determining the length (the horizontal direction) and the width (the vertical direction) of the slit hole **50a** as the occasion may demand. The extruding members **46** are stuck on the ribs **44a** so as to protrude by substantially 1 mm from the slit hole **50a**. In this embodiment, not a hole within which a projection is moved (reference character **52a** in FIG. 30) or the like, but only the toner supplying port **54**, is formed in a toner introducing cover **52'** since any shutter member is not disposed.

The construction in which the toner supply unit **6** is attached to or detached from the apparatus body has been described in the aforementioned embodiment. Hereinafter, there will be described in detail in relation to the construction. As shown in FIG. 32, a pin **37** is disposed in the apparatus-body front plate **59**. Herein, the pin **37** is inserted into a positioning hole **150** on the end side of the toner supply unit **6** when the toner supply unit **6** is installed in the apparatus body. Further, a pin (not shown) which is inserted into a positioning hole **151** is disposed in the apparatus-body front plate **59**. Thereby, the toner supply unit **6** can be mounted with high precision at a predetermined position of

the apparatus body. Then, the toner supply unit 6 is fixed by the stopper 112 when being mounted completely in the apparatus body.

In FIG. 33, there is shown a state where the toner supply unit 6 has been drawn out of the apparatus body. Herein, step portions 42d, 42e are formed in the receiving stand 42, and notch portions 108a, 108b are formed in the guide plate 108. While the toner supply unit 6 is drawn out of the apparatus body, the step portions 42d, 42e are hooked by the notch portions 108a, 108b so that the toner supply unit 6 is kept in the state of being shown in FIG. 33.

In the state mentioned above, the toner bottle 38 which has been filled with toner is placed on the receiving stand 42, as shown by an arrow. Thereafter, the toner supply unit 6 is installed while being slid in the direction of being shown by the arrow on the guide plate 108.

Next, a variation of the mechanism by which the toner bottle 38 is driven to rotate will be described, as shown in FIG. 34. In this variation, a joint 152 having a diameter of S used in lieu of the joint 62, and a plurality of convex portions 152a are formed on the end plane thereof. In the bottom part of the toner bottle 38, on the other hand, a plurality of ribs 153f are disposed inside of a concave portion 153e having a diameter of S.

In this construction, the concave portion 153e in the bottom part of the toner bottle 38 is positioned by becoming engaged with the joint 152 when the receiving stand 42 in which the toner bottle 38 is set up is pushed in. When the drive portion 60 starts driving, the side of the convex portions 152a of the joint 152 comes into contact with the ribs 153f of the concave portion 153e, and thereby the drive is transferred to the toner bottle 38.

What is claimed is:

1. An image forming apparatus, comprising:
a toner supply unit which is directly or indirectly attached to and detached from a body of the image forming apparatus having a toner receiving port, said toner supply unit having:
a toner supply port facing said toner receiving port when said toner supply unit is attached to the body of the image forming apparatus; and
a shutter member for opening and closing said toner supply port;
wherein said shutter member consists of a bendable elastic member and a holding member for holding said bendable elastic member, said shutter member intersecting with an opening surface of said toner supply port; and
said toner supply unit has a guiding portion for bending and guiding said bendable elastic member along said toner supply port.

2. An image forming apparatus according to claim 1, wherein said shutter member has a projection and, on a side of the body of the image forming apparatus, a guide rib is disposed which is engaged with said projection of said shutter member and serves to open or close said shutter member.

3. An image forming apparatus according to claim 1, wherein said toner supply unit has an elastic sealing member with which an end of said bendable elastic member comes in contact when said shutter member closes said toner supply port.

4. An image forming apparatus according to claim 1, wherein said toner supply unit has a deformation regulating guide for regulating deformation of said bendable elastic member suffered when said bendable elastic member is

moved, said deformation regulating guide facing a surface of said bendable elastic member which is a reverse of a contact surface of said bendable elastic member brought into contact with said guiding portion.

5. An image forming apparatus according to claim 2, wherein said toner receiving port and said guide rib are formed in a process cartridge containing at least an image bearing medium and a developing unit which are formed integrally with each other, said process cartridge being attached to and detached from the body of the image forming apparatus, said process cartridge having a second shutter member for opening and closing said toner receiving port, said second shutter member having a second projection, said toner supply unit having guiding ribs which are engaged with said second projection and serve to open and close said second shutter member, said guide rib and said guiding ribs having engagable trapezoidal shapes.

6. An image forming apparatus according to claim 2, wherein said toner supply unit has an elastic sealing member with which an end of said bendable elastic member comes in contact when said shutter member closes said toner supply port.

7. An image forming apparatus according to claim 3, wherein said toner supply unit has a deformation regulating guide for regulating deformation of said bendable elastic member suffered when said bendable elastic member is moved, said deformation regulating guide facing a surface of said bendable elastic member which is a reverse of a contact surface of said bendable elastic member brought into contact with said guiding portion.

8. An image forming apparatus according to claim 4, wherein said shutter member has a projection and, on a side of the body of the image forming apparatus, a guiding rib is disposed which is engaged with said projection of said shutter member and serves to open or close said shutter member.

9. An image forming apparatus according to claim 6, wherein said toner receiving port and said guide rib are formed in a process cartridge containing at least an image bearing medium and a developing unit which are formed integrally with each other, said process cartridge being attached to and detached from the body of the image forming apparatus, said process cartridge having a second shutter member for opening and closing said toner receiving port, said second shutter member having a second projection, said toner supply unit having guiding ribs which are engaged with said second projection and serve to open and close said second shutter member, said guide rib and said guiding ribs having engagable trapezoidal shapes.

10. An image forming apparatus according to claim 6, wherein said toner supply unit has a deformation regulating guide for regulating deformation of said bendable elastic member suffered when said bendable elastic member is moved, said deformation regulating guide facing a surface of said bendable elastic member which is a reverse of a contact surface of said bendable elastic member brought into contact with said guiding portion.

11. An image forming apparatus according to claim 10, wherein said toner receiving port and said guide rib are formed in a process cartridge containing at least an image bearing medium and a developing unit which are formed integrally with each other, said process cartridge being attached to and detached from the body of the image forming apparatus, said process cartridge having a second shutter member for opening and closing said toner receiving port, said second shutter member having a second projection, said toner supply unit having guiding ribs which are engaged

25

with said second projection and serve to open and close said second shutter member, said guide rib and said guiding ribs having engagable trapezoidal shapes.

12. A toner supply unit, comprising:

a toner bottle having a toner discharging port formed in a middle of an end of a cylindrical body of said toner bottle;

bottle holding means for holding said toner bottle substantially horizontally in a state in which toner can be introduced from said toner discharging port into a toner introducing portion of a developing unit; and

rotational driving scans for rotating said toner bottle held by said bottle holding means around a central axis of said toner bottle extending in a longitudinal direction of said toner bottle;

wherein said toner bottle can be attached to and detached from a body of said toner supply unit in the direction of the central axis in a state in which said toner bottle is held by said bottle holding means.

13. A toner supply unit according to claim 12, wherein said toner bottle has a concave portion formed in a middle of the other end opposite to the end of the cylindrical body of said toner bottle in which said toner discharging port is formed, and said rotational driving means has an engagement portion for communicating a driving force by engagement with said concave portion.

14. A toner supply unit according to claim 12, wherein said toner bottle has convex portions formed in a middle of the other end opposite to the end of the cylindrical body of said toner bottle in which said toner discharging port is formed, and said rotational driving means has engagement portions for communicating a driving force by engagement with said convex portions.

15. A toner bottle, comprising:

a cylindrical body as a container for containing a toner; a bottom portion with which an end of said body is closed; and

a port for discharging a toner, said port being narrowly formed in another end opposite to the end of said bottom portion;

said cylindrical body having a spiral groove formed in an inner wall of said cylindrical body, said spiral groove spirally and consecutively extending from a side of said bottom portion toward said port so as to convey a toner through said spiral groove and discharge the toner from said port in accordance with rotation of said toner bottle;

wherein projections extending in a longitudinal direction of said toner bottle are formed to communicate a rotational force to said toner bottle on an outer surface of said bottom portion and away from a line of a central axis of said cylindrical body.

16. A toner bottle according to claim 15, further comprising a positioning center for determining a central position, said positioning center being formed on the outer surface of said bottom portion and existing on the line of the central

26

axis of said cylindrical body, said positioning center extending in the longitudinal direction more than said projections.

17. A toner bottle according to claim 15 or 16, wherein said bottom portion has a convex circumferential portion on which a ring having a predetermined width in the longitudinal direction is rotatably fitted by means of fitting means, said fitting means preventing said ring from coming off from said body of the toner bottle in the longitudinal direction when said ring rotates.

18. A toner bottle according to claim 17, wherein the predetermined width of said ring is set so that an outer-sided end surface of said ring in the longitudinal direction is located outer than said positioning center.

19. A toner bottle according to claim 17, wherein said ring has a projection formed on a circumferential surface of said ring, said projection extending radially and being engaged with a concave portion of an immovable member.

20. A toner bottle according to claim 17, wherein said ring has a projection by which the toner bottle is prevented from being interchanged with another type of toner bottle.

21. A toner bottle according to claim 17, wherein said fitting means comprises stoppers formed on an inner surface of said ring, elastic claws, and said convex circumferential portion held between said stoppers and said elastic claws.

22. A toner bottle according to claim 21, wherein said convex circumferential portion is formed smaller in diameter than said cylindrical body of the toner bottle, the diameter of said convex circumferential portion being set so that said elastic claws are within an end plane space defined by a radial difference between said convex circumferential portion and said cylindrical body in a state in which said ring is fitted on the toner bottle.

23. A toner bottle according to claim 15, wherein: a cylindrical intermediate portion is formed in a part of said cylindrical body closer to said port than said bottom portion, said cylindrical intermediate portion being engaged with a cylindrical bottle-holding member for holding the toner bottle and guiding a toner discharged from said port to a predetermined position by simultaneous rotation with the toner bottle; and small projections are formed on an outer circumferential surface of said cylindrical intermediate portion, said small projections rotatably positioning the toner bottle to be adjusted to a center line of an inner circumferential part of a toner receiving stand.

24. A toner bottle according to claim 15, wherein: a cylindrical intermediate portion is formed between said port and said cylindrical body, said cylindrical intermediate portion being engaged with a cylindrical bottle-holding member for holding the toner bottle and guiding a toner discharged from said port to a predetermined position by simultaneous rotation with the toner bottle; and

driving claws for communicating torque to said bottle holding member are formed on an end surface of said cylindrical intermediate portion on a side of said port.

* * * * *
